UNITED STATES PATENT OFFICE.

THEODORE A. WILLARD, OF CLEVELAND, OHIO, ASSIGNOR TO THE WILLARD STORAGE BATTERY COMPANY, OF CLEVELAND, OHIO, A CORPORATION OF OHIO.

DESIGN FOR A STORAGE-BATTERY HANDLE.

47,978.

Specification for Design.

Patented Oct. 12, 1915.

Application filed July 6, 1915. Serial No. 38,322. Term of patent 7 years.

To all whom it may concern:

Be it known that I, THEODORE A. WILLARD, a citizen of the United States, residing at Cleveland, in the county of Cuyahoga and State of Ohio, have invented a new, original, and ornamental Design for Storage-Battery Handles, of which the following is a specification, reference being had to the accompanying drawing, forming part thereof.

In the drawing Figure 1 is a front view,

and Fig. 2 is an edge or side view, of a storage battery handle showing my new design.

I claim:

The ornamental design for a storage battery handle substantially as shown.

THEODORE A. WILLARD.

Witnesses:

L. I. PORTER,
E. B. GILCHRIST.
